(57) **CLAIM**

The ornamental design for a utility rack with panels as shown and described.

DESCRIPTION

FIG. 1 is a perspective view of a utility rack with panels, in a configuration of use, showing our new design.

FIG. 2 is an upper perspective view thereof.

FIG. 3 is a lower perspective view thereof.

FIG. 4 is a rear view thereof.

FIG. 5 is a front view thereof.

FIG. 6 is a left side view thereof.

FIG. 7 is a right side view thereof.

FIG. 8 is a top view thereof.

FIG. 9 is a bottom view thereof.

FIG. 10 is an upper perspective view thereof, with the rear panel open.

FIG. 11 is a lower perspective view thereof, with the rear panel open.

FIG. 12 is a rear view thereof, with the rear panel open.

FIG. 13 is a front view thereof, with the rear panel open.

FIG. 14 is a left side thereof, with the rear panel open.

FIG. 15 is a right side view thereof, with the rear panel open.

FIG. 16 is a top view thereof, with the rear panel open.

FIG. 17 is a bottom view thereof, with the rear panel open.

FIG. 18 is an upper perspective view thereof, with the rear and side panels open.

FIG. 19 is a lower perspective view thereof, with the rear and side panels open.

FIG. 20 is a rear view thereof, with the rear and side panels open.

FIG. 21 is a front view thereof, with the rear and side panels open.

FIG. 22 is a right side view thereof, with the rear and side panels open.

FIG. 23 is a left side view thereof, with the rear and side panels open.

FIG. 24 is a top view thereof, with the rear and side panels open; and,

FIG. 25 is a bottom view thereof, with the rear and side panels open.

The broken lines in the figures show portions of the utility rack with panels or environmental matter that form no part

(Continued)

of the claimed design. The shade lines and shading in the figures show contour and not surface ornamentation.
